UNITED STATES PATENT OFFICE.

JOHN E. LEE, OF CHIPPEWA FALLS, WISCONSIN.

BUCKLE.

SPECIFICATION forming part of Letters Patent No. 314,693, dated March 31, 1885.

Application filed July 21, 1884. (No model.)

To all whom it may concern:

Be it known that I, JOHN E. LEE, a citizen of the United States, residing at Chippewa Falls, in the county of Chippewa and State of Wisconsin, have invented a new and useful Improvement in Buckles; and I do hereby declare that the following is a full, clear, and exact description of the invention, which will enable others skilled in the art to which it appertains to make and use the same, reference being had to the accompanying drawings, forming part of this specification.

My invention has for its object to provide an improved buckle for harness, belting, metal bands, and other purposes, which can be used in its single and double form, and will retain the bands, &c., introduced within the same singly and in loops at different angles from opposite movement and without the inconvenient protrusion of the tongue beyond the buckle; and it consists in the novel construction and combination of its several parts, which will be first fully described, and specifically pointed out in the claim.

25 In the drawings, Figure 1 is a perspective view of the buckle. Fig. 2 is a plan view of the buckle in a reverse position to that seen in Fig. 1. Fig. 3 is a longitudinal sectional view through the line x x of Fig. 2.

30 A represents the complete buckle. a a are the sides of the same. a' a' are the transverse end bars on outer face of the buckle.

a^2 a^2 are the transverse end bars on the inner face of the buckle. a^3 a^3 are the forked ends of the sides a a . a^4 is the aperture in the transverse end bar, a^2 . a^5 is a raised rim on the inner side of the transverse end bar, a^2 , and around the aperture a^4 . a^6 is a transverse central pivot through the sides a a of the buckle. B is a flanged tongue-plate on pivot a^6 , and b the hook or stud upon the same. b' is a slot in the hinge b^2 . b^2 is the hinge of the flanged tongue-plate B on the central pivot, a^6 . c is the ordinary form of tongue on central pivot, a^6 .

45 In the construction of my improved buckle I make the side plates, a a , which extend in the longitudinal direction of the tongue, slightly wider than the relative thickness of the bands, which are required to be looped or 50 folded one upon another and inserted in the buckle.

Upon the upper and lower longitudinal end portions of the sides a a , and connecting them together, are formed the transverse bars a' a' and a^2 a^2 , the latter bars, a^2 a^2 , being slightly 55 wider than the former bars, a' a' , and are placed upon the under side of the buckle. The ends of the longitudinal side bars, a a , I make in a forked shape, as at a^3 , which permits the lateral spread of the bands when in the buckle. 60 The distance vertically between the end bars upon the outer and inner faces of each end of the buckle is, as seen, sufficient to afford an entrance longitudinally of a double band. A pivot, a^6 , is then inserted in a central trans- 65 verse relation to the width of and through the longitudinal side of the buckle and the tongue c attached thereto in the ordinary manner. I then form a flanged tongue-plate, B, of sufficient width to play freely between the sides 70 a a and transverse bars a' a' of the buckle, and upon one end the hinge b^2 , which is bent around the pivot a^6 . A slot, b' , is made through the hinge b^2 of the flanged tongue-plate B, and, ex- 75 tends a slight distance in the plate, permits the hinged end b^4 of the tongue c to play on the same central pivot. The opposite end of the flanged tongue-plate B extends outwardly in the direction of and near to the transverse bar a' , slightly within the radius described 80 from the pivotal point of the flanged tongue-plate B and the inner edge of the said bar.

Upon the inner side and at the end of the flanged tongue-plate B, in a direct line with the tongue c, I form a hook, b, corresponding 85 with the free end of tongue c, bent at right angles and equal in length to half the width of the sides a a .

Through the transverse bar a^2 beneath and in the path of the hook b, I make the aperture a^4 , and above and in vertical line with the said aperture upon the inner side of the transverse bar the raised rim a^5 .

In the operation of my improved buckle the band or strap is introduced singly at first 95 between the transverse bars a' and a^2 within the buckle and below the central pivot to the required distance, the flanged tongue-plate B being upheld until the proper hole in the band or strap is reached when it is dropped 100 upon the same, the hook b entering the hole in the strap and also the aperture a^4 in the cross-

bar. The opposite end of the band may be doubled, as seen in Fig. 3, to form a loop, and passed in the same direction as the first within the buckle, the tongue *c* being permitted to 5 enter the proper hole in the band, and thence over the pivot and upon the flanged tongue-plate *B* outwardly between the transverse bars and in union with its fellow band, thereby enabling the folds of the strap to be compactly 10 retained in the buckle on either side of the tongue-plate.

It will be observed that when united with the strap of a harness the side of the buckle presented to the animal is perfectly smooth 15 and obviates the danger that would result from a protruding tongue swinging with the play of the strap against the animal's head or body.

The old form of tongue *c* may be entirely 20 dispensed with for many purposes, as in the use of a metal band it would be impracticable, while in my improved buckle a metal band is as readily secured as any other kind.

When it should become necessary to use 25 my buckle with the bands running at right angles thereto, or in the line of the pivot, and retained in such relation, the opening *a*² is continued longitudinally in the sides *aa*, as shown in dotted lines, and the bands inserted 30 in that relation, the opposite band serving to hold the flanged tongue *B*, with its hooks, firmly upon the band beneath. The raised rim upon the inner side of the transverse bar *a*² enables the hook *b* to retain itself more firmly 35 when a band is secured in the buckle and subjected to great strain. It also enables the hook *b* to be made shorter and extend but a slight distance within the socket to afford the bearing required.

It will be seen, as in dotted lines of Fig. 40 1, that the ordinary tongue, *c*, bent at right angles at one end to form the hook *b*, and hinged to the central pivot singly, and also with the slotted hinge, may be used. I have found, however, that the flanged tongue-plate, 45 when between the bands, especially in large buckles, affords a greater resistance to an upward play than the single tongue.

An advantage is also obtained in my improved double buckle, in that placing the 50 tongue *c* and the hook upon the flanged tongue in the same longitudinal plane enables them to be readily secured in the holes in the band and obviating the necessity of bending the ends of the tongues in opposite directions to 55 obtain these results. I am also better enabled in my invention to prevent the slackening of the loops or bands in the buckle and permit the tension to be brought upon the buckle from opposite directions. 60

Having fully described my invention, what I now claim as new, and desire to secure by Letters Patent, is—

The buckle provided with side and open end bars, a suitable base-plate, and central 65 cross-bar, substantially as described, a tongue pivoted to the central cross-bar and extending in one direction and adapted to rest on one of the end bars, and a tongue-plate pivoted to the same cross-bar and extending in the 70 opposite direction from the tongue, and provided with a stud upon its under side adapted to engage an aperture in the said base-plate, substantially as described.

JOHN E. LEE.
